Primary Examiner—Holly H. Baynam*Assistant Examiner*—Cynthia M. Chin(74) *Attorney, Agent, or Firm*—Young Basile**CLAIM**

The ornamental design for a collapsible enclosure, as shown and described.

DESCRIPTION

FIG. 1 is a perspective view of the collapsible enclosure showing my new design;

FIG. 2 is a front elevational view of the collapsible enclosure of FIG. 1;

FIG. 3 is a rear elevational view of the collapsible enclosure of FIG. 1;

FIG. 4 is a side elevational view of the collapsible enclosure of FIG. 1, the opposite side being a mirror image thereof; FIG. 5 is a top plan view of the collapsible enclosure of FIG. 1; and,

FIG. 6 is a bottom plan view of the collapsible enclosure of FIG. 1.

The broken lines showing additional detail are for illustrative purposes only and form no part of the claimed design.
